TYPEWRITING MACHINE

Laurence B. Hill and Edson G. Moshier, Syracuse, N. Y., assignors to L. C. Smith & Corona Type-writers, Inc., Syracuse, N. Y., a corporation of New York

Application August 8, 1941, Serial No. 406,016

4 Claims. (Cl. 197—114)

The invention relates to improvements in typewriting machines and more particularly to improvements in paper feeding mechanism for such machines. The improvements particularly relate to means for feeding webs of printed forms across the writing line of the typewriting machine for typing successive forms of the web of forms. In typing webs of forms it is highly desirable to have some means for advancing to the writing line of the machine rapidly and easily the first line of each form to be typed. It is also desirable to be able to line space individual forms for typing several lines of each individual form. For example, in typing a web of check forms, it is frequently desirable to type the name of the payee on one line and to type on one or more successive lines the address of the payee.

The general object of the invention is to provide simple and efficient means for typing webs of forms of the character above described and provide means for registering the leading edge of each form web introduced into the paper feed mechanism of the machine and for positioning said edge at a definite point behind the writing line of the machine.

To the foregoing and other ends which will hereinafter appear, the invention consists of the features of construction, arrangements of parts, and combinations of devices hereinafter particularly described and pointed out in the appended claims.

In the accompanying drawings showing the preferred embodiment of the invention in connection with the well-known L C Smith typewriting machine:

Figure 1 is a fragmentary plan view of the machine with certain parts being broken away.

Figure 2 is a fragmentary view approximately on the line 2—2 of Figure 3, showing more particularly the paper feed roll mechanism and the leading edge gauging and registering mechanism of the machine.

Figure 3 is a sectional view on the line 3—3 of Figure 1.

Figure 4 is a sectional view on the line 4—4 of Figure 1.

Figure 5 is a sectional view on the line 5—5 of Figure 1.

Figure 6 is a sectional view on the line 6—6 of Figure 1.

Figure 7 is a sectional view on the line 7—7 of Figure 1 showing the sweep line-spacing mechanism operating on the platen and beginning to turn the platen to feed the paper.

Figure 8 is a view similar to Figure 7 showing

the parts positioned as at the end of the operating stroke of the sweep line-spacing mechanism and having superimposed on the parts illustrated, in broken lines, the ratchet wheel of the standard line spacing mechanism and the ratchet detent of the standard line spacing mechanism.

Figure 9 is a detail sectional view on the line 9—9 of Figure 2 showing the paper feed rolls engaged with the platen and the leading end 10 registering and stopping means in inoperative position.

Figure 10 is a similar detail sectional view taken on the line 10—10 of Figure 2.

Figure 11 is a view similar to Figure 10 showing the paper feed rolls cast off from the platen and the leading edge stopping and registering means in operative position.

Figure 12 is a detail sectional view on the line 12—12 of Figure 2 showing the paper feed rolls in their operative position.

Figure 13 is a detail sectional view on the line 13—13 of Figure 9.

Figure 14 is a detail sectional view on the line 14—14 of Figure 13.

Only as much of the known machine as is necessary to an understanding of the present invention is shown and will be described.

The machine comprises a main frame 15 upon which is mounted to travel transversely of the machine on the usual ball bearings the usual platen carriage 16. Extending across the front of the carriage 16 and affixed to the usual end plates of the carriage, is the usual bar 17 and the usual letter space scale bar 18. On the bar 17 may be mounted the usual paper fingers 19.

The shaft of the usual cylindrical platen 20 is rotatively journaled in the usual bearings 21 at opposite ends of the carriage, the shaft 22 of the platen extending horizontally transversely of the machine as usual. The usual pair of twirler knobs or finger wheels 23 are connected with the platen at opposite ends of the carriage for rotating the platen in either direction. The usual line space ratchet wheel 24 is held to the platen adjacent the left hand end of the carriage and is operable by the usual line space mechanism, settable to rotate the platen either 1, 2, or 3 tooth spaces of the ratchet 24. This ordinary or standard line space mechanism can be of any suitable construction, the construction shown being that of the L C Smith machine hereinbefore referred to. Said ordinary line spacing mechanism in the construction shown comprises generally the bell crank line space hand lever 25 journaled on the vertical pivot 26 on the carriage.

55

and having a stop lug 27 engageable with the left hand end of the carriage to limit the return movement of the line space lever which is effected through the usual line space lever return spring (not shown). The usual link 28 is pivotally connected at its opposite ends with one arm of the line space lever at 29 and its other end at 30 with the usual pawl carrier 31. The pawl carrier 31 is pivoted on the carriage at 32 and the line space pawl 33 is pivoted on the pawl carrier at 34. The line space pawl carries the usual pin 35 which, during the latter part of the return stroke of the line space lever, rides over the usual line space regulator 36 which is pivoted to the carriage at 37 and is settable by the usual handle 38 (Figure 1) affixed to said regulator to cause the pawl in the known manner to rotate the ratchet 24 either 1, 2, or 3 letter spaces. Said pawl has the usual arm 39 engageable with the ratchet 24 to limit the operating stroke of the line space lever and prevent overthrow of ratchet 24.

The usual spring-urged detent 40 for ratchet 24 is pivoted on the carriage at 41 and is normally urged between two adjacent teeth of the ratchet by the usual ratchet detent spring 42 (Figure 4) to hold the platen against accidental rotation.

By means of this usual line spacing mechanism the platen may be rotated by a full stroke of the line space lever either 1, 2, or 3 tooth spaces of the ratchet depending on the adjustment of the regulator 36 as is common in the art.

Extending below the platen, and affixed to the carriage 16 and to the bar 17 adjacent opposite ends of the platen, are two supporting brackets 51 which are of U-shape in cross-section, the side flanges of each of which brackets 51 extend upwardly. Fixed to the flanges of this pair of brackets 51 are the ends of the usual two rods 43 and 44 which are spaced fore and aft of the machine and extend transversely thereof parallel to the axis of the platen. Adjacent opposite ends of said rod 43 are pivoted the usual two arms 45, the front ends of which support the respective ends of the usual front feed roll shaft 46 carrying the usual front feed rolls 47. Adjacent opposite ends of the rear rod 44 are pivoted the usual two arms 48, the rear ends of which support opposite ends of the usual rear feed roll shaft 49 carrying the usual rear feed rolls 50.

The usual concave paper apron or deflector 52 is supported beneath the platen in the usual manner, said apron having the usual pair of ears 53 journaled on the front feed roll shaft 46, and having the usual lug 54 supported on the usual small roller 55 mounted on the rear feed roll shaft 49. The usual two pressure springs 56, for normally urging the feed rollers toward the platen, are wrapped around the rods 43 and 44 adjacent opposite ends of said rods and each engaged adjacent its opposite ends beneath the front and rear feed roll shafts, as more clearly shown in Figure 12.

The usual feed roll cast-off mechanism for casting off the feed rolls to facilitate the insertion of paper in the machine is provided. Each of the arms 45 has the usual rearward extension 57 overlapping the usual forward extension 58 of its companion arm 48. A rock shaft 59 is journaled in the upstanding flanges of the brackets 51 and in the right hand end of the platen carriage 16. Affixed to this rock shaft is the usual pair of tappets or cams 60 having forwardly extending noses closely overlapping the usual rearward extensions 61 of arms 48 in the cast-on, or paper-feeding, position of the feed rolls. The rock shaft 59

has the usual forwardly extending rock arm 62 which is located at the right hand end of the carriage provided at its forward end with a laterally extending pin 63 engaged in the usual cam slot 64 in the paper feed roll cast-off lever 65. Lever 65 is journaled, as usual, on the right hand end of the carriage at 66 to swing fore and aft of the machine. The cam slot 64 has the usual upward enlargement 64a in its upper edge adjacent the forward end of the slot to releasably latch the feed rolls in cast-off position when the handle end of lever 65 is drawn forward to its full limit of motion.

The paper feed rollers are contactive with the platen in their operative or "on" position through clearance notches in the forward and rear edges of the paper apron 52. When the handle end of the lever 65 is swung forwardly, the tappets 60 engage extensions 61 of arms 48 and swing these arms to lower the rear feed rollers, thereby causing the extensions 58 of arms 48 to engage extensions 57 of arms 45 and swing the front feed rollers away from the platen. When the front and rear forward rollers are swung downwardly away from the platen, the paper apron 52 is also lowered, as will be obvious.

Also mounted on the carriage in the usual manner is the usual paper table 67 for directing the paper forwardly and downwardly between the platen and the paper apron 52. A portion of this paper table 67 is shown in Figures 1, 10, and 11.

It will be obvious that the detailed construction of the paper feed mechanism above described, which is the paper feed mechanism of the known L C Smith machine, may be varied. The new features of the machine whereby the objects of the invention hereinbefore pointed out are accomplished will now be described.

Stopping and registering means is provided for squaring the leading edge of the sheet or web of printed forms with the writing line of the machine and arresting introduction of the web into the machine at a predetermined distance to the rear of the writing line. In the machine illustrated, the writing line is indicated by the line 68 in Figure 8. In other words, the lowest positions of such characters as L, M, N, and the like impinge the platen along a horizontal line coincident with the point at which the radial line 68 intersects the periphery of the platen.

The stopping means comprises two registering stops 69 located adjacent opposite ends of the platen and extending beneath the platen. Each stop 69 is formed of a bar of thin spring steel having its forward end bent upwardly for contact with the under side of the platen when the stop is in effective position. Each stop bar 69 is adjustably fixed intermediate its ends to an axle 70 by means of a screw 71 which extends through a longitudinal slot 72 in the bar. The arm of each stop bar forward of axle 70 is movable up and down through the adjacent one of two fore-and-aft extending slots 73 in the paper apron 52. Screws 71 are accessible through slots 73, when the platen is removed from its bearings, to permit each stop 69 to be adjusted fore and aft of the machine, or transversely of the platen. Each stop bar 69 is held by its anchoring screw 71 in a notch 74 (Figure 13) formed in the axle 70 of the stop bar. The longitudinal side edges of each stop bar engage the side walls of the slot in its axle to prevent accidental turning of the stop bar about the shank of the screw 71. Each stop bar 69 extends rearwardly from its axle 70, and two tappets 75 which are fixed on the rock

shaft 59 overhang the rearwardly extending arms of the two stop bars 69.

The tappets 75, in the normal position of the hand lever 65, are spaced slightly farther above the rear ends of the stop bars 69 than the tappets 60 are spaced above the extensions 61 of arms 48. It is thus possible to rock the hand lever 65 forward slightly to an extent sufficient to relieve the pressure of the paper feed rolls on the platen to permit straightening of a paper sheet in the machine without throwing the stops 69 into sheet stopping position. It will be obvious that, when the arm 65 is thrown completely forward from the position shown in Figure 3, both sets of paper feed rolls 47 and 50 will be cast off from the platen into the position shown in Figure 11 and the two stops 69 will be rocked to press their upturned forward ends yieldingly against the under side of the platen into the position shown in Figure 11.

In this position of the feed rolls and stops, the paper sheet or web may be introduced into the machine down over the paper table 67 and between the platen and the apron 52 until the front edge of the sheet or web is arrested and is registered or squared with the writing line of the machine by contact of said edge with the upturned forward ends of the stop arms 69. The lever 65 is releasably held to maintain the stops and the paper feed rolls in the position shown in Figure 11 until the lever 65 is pushed rearwardly. When the lever 65 is pushed rearwardly to its normal position shown in Figure 3, the feed rolls and paper apron are restored to normal position to press the sheet to the platen, and the forward ends of the stops 69 move downwardly through the slots 73 into the ineffective position shown in Figures 9 and 10.

To simplify the construction and mounting of the two stops 69 and facilitate assembly thereof in the machine, the axle 70 of each stop has a reduced cylindrical bearing portion 76 inserted in a circular bearing aperture in one of the upstanding flanges of the adjacent bracket 51, and adjacent its other end, each axle has a reduced cylindrical bearing portion 77 engaged in an open notch or slot 78 in the other upstanding flange of the adjacent bracket 51. Outwardly beyond the bearing portion 77 of each axle, the axle is formed with a cylindrical head 79 provided adjacent the outer face of the slotted flange of bracket 51 with a kerf 80 through which extends the rear arm of one of two springs 81. The rear arm of each spring 81, in the normal position of the stops 69 and feed rollers shown in Figure 9, engages the front end edge of the bottom of kerf 80 in axle 70 of the associated stop as shown in Figure 14. Each spring 81 is provided intermediate its ends with a downward bend or bow 82 in which is seated the adjacent end of rod 44, while the forward end of each spring 81 is engaged over the adjacent end of the rod 43. The springs 81 thus are normally tensioned to urge each of the stops 69 to their ineffective position and hold them there. The springs 81 also releasably hold the axles of the stops 69 in their mountings in brackets 51. The ends of rods 43 and 44 are grooved as indicated in dotted lines in Figure 9 to receive the springs 81.

It will be observed that the stops 69 will arrest the leading end of a work sheet or web being introduced into the machine at a predetermined distance from the writing line 68, and said stops

also permit the operator to square the leading end of the work sheet with the writing line.

To permit the arrested and registered work sheet to be fed and typed on predetermined lines of a series of blank forms printed on the work sheet or web, means is provided which will now be described.

Secured to the right hand end of the platen by means of screws 83 is a ratchet 84. The heads of screws 83 are countersunk in the ratchet. The number of teeth of the ratchet 84 is an aliquot part of the number of teeth of the ratchet 24. In the construction shown, the ratchet 24 has 35 teeth and the ratchet 84 has 5 teeth. The ratchet 84 is formed of a flat circular metal disk provided with 5 notches 85 adapted to receive the nose of a suitable driving pawl hereinafter described. The five coarse teeth thus provided on the ratchet 84 have long tops 86 which are concentric with the axis of the platen from notch to notch.

To permit the platen to be rotated through the ratchet 84, a sweep line space handle 87 is provided adjacent the right hand end of the carriage. This handle has a hub 88 journaled on a bearing 89 which extends horizontally transversely of the machine and is held to the right hand end of the carriage 16. The handle 87 is normally urged into the position shown in Figures 1, 3, and 5 by means of a suitable return spring 90 which is coiled about the hub of the handle and has one end engaged with a pin 91 on the handle, its other end engaged with the adjacent end of the carriage.

At its lower end said handle is formed with a sector 92, the toothed edge of which is concentric with the pivotal axis of the handle. The teeth of the sector 92 mesh with the teeth of a pinion 93 which is loosely journaled on the shaft 22 of the platen and has rigidly affixed to the inner end thereof a pawl carrying arm 94. The pawl carrier 94 has a shoulder 95 which, in the normal returned position of the handle 87, is seated on the top edge of the bar 17 on the carriage. Pivoted on the pawl carrier at 96 is a pawl 97, the nose of which is constantly urged inward toward the periphery of the ratchet 84 by means of a spring 98 anchored to the pawl and to the pawl carrier. In the normal position of the pawl carrier, the nose of the pawl 97 is held rocked against the pull of the spring 98 into the position shown in Figure 6, in which position the nose of the pawl does not contact the periphery of the ratchet 84 and can not enter any notch 85.

The pawl 97 is rocked into this position during the last part of the return movement of the pawl carrier and handle 87 by means of a lever 99 pivoted to the pawl carrier at 100. The lever 99 has an arm engageable at one edge thereof with the bar 17 and at the other edge thereof with a tail 101 of the pawl 97. The lever 99 has another arm engageable with a pin 102 on the pawl carrier, to which pin one end of the spring 98 is also anchored. During the latter part of the return motion of the pawl carrier 94, the lower edge of the lever 99 contacts bar 17 shortly before shoulder 95 of the pawl carrier contacts that bar, thereby throwing the pawl 97 entirely out of engagement with the ratchet before the return motion of handle 87 is arrested by engagement of shoulder 95 with bar 17.

After a work sheet has been registered and handle 65 pushed rearward, when the handle 87 is pulled forward to the limit of its motion, the nose of pawl 97 will first engage the ratchet 84,

as shown in Figure 7, and the ratchet and the platen will thereafter be turned through three tooth spaces of ratchet 84 and twenty-one tooth spaces of the ratchet 24, the spacing stroke of the handle 87 being limited by engagement of the back of pawl 97 with a stud 103 which is rigidly attached to the right hand end of the carriage and projects inwardly therefrom. The engagement of pawl 97 with the stud 103 not only arrests rotation of the platen, but jams the nose of the pawl tightly into that notch 85 with which the nose is engaged to thereby prevent accidental overthrow of the ratchet. The arc of rotation imparted to the platen by the three tooth-spaces advance of the ratchet 84 is sufficiently great to carry the leading edge of a sheet introduced into the machine and registered by means of the stops 69 from the stop arrested position of the sheet across the writing line of the machine a predetermined extent into position for typing upon the initial line of the first form printed on the web or sheet. Thereafter the web may be line spaced in short steps of either one, two, or three tooth spaces of the ratchet 24 by successive actuations of lever 25 of the usual line space mechanism hereinbefore described. It is possible to type as many as six single spaced lines upon each individual form with the mechanism shown.

It will be observed that, whether or not the standard line spacing mechanism is operated, the platen will, upon the next actuation of the handle 87, be turned only far enough to cause a total second advance of the sheet or web to an extent equal to that which the sheet was first advanced on the preceding operation of the handle 87, so that each succeeding operation of the handle 87 will bring to the writing line of the machine the first writing line of the next succeeding form on the web.

The construction shown is particularly designed for typing the name and address of the payees of checks initially printed seriatum as a series of blank check forms on a transversely perforated paper web. It will be observed that, when such a web of blank check forms is introduced and registered in the machine through the medium of stops 69, the stops then thrown out and the paper feed rolls thrown on, and the handle 87 then pulled forwardly and released, the web is advanced far enough to present at the writing line of the machine the first writing line of the first form for typing thereon the name of the payee. The address of the payee can then be typed on the first form, such typing requiring one or more successive operations of the line space lever 25. Thereafter, by again pulling the handle 87 forward and releasing it, the next form of the web will be advanced to bring it into position for typing of the name of the payee of the second check. Where the handle 25 is operated one or more times after an operation of handle 87, the nose of the pawl 97 during the initial portion of the next operation of handle 87 will ride along the arcuate top 86 of the adjacent tooth of the ratchet 84 until the nose of the pawl enters that notch 85 of ratchet 84 which has been advanced beyond the nose of the pawl by actuation of the handle 25.

Important features of the invention reside in the facts that the number of teeth of the ratchet 84 is an aliquot part of the number of teeth of the ratchet 24, and the driving pawl 97 has an invariably fixed throw.

Another feature of the invention resides in the fact that, normally, both the pawl 83 and

the pawl 97 are out of engagement with their respective ratchets, so that the platen may be rotated either forwardly or backwardly against the resistance of the spring detent 40 by means of either one of the finger wheels 23.

Another feature of the invention consists in making the stopping levers 69 of thin spring steel so that the up-turned sheet-arresting forward ends of said levers may be resiliently pressed against the under side of the platen by tappets of 75 code frequency modulated 25 times a minute.

We claim:

1. In a typewriting or other machine of the kind having a rotatively journaled roller platen for backing paper to receive type impressions, a sweep line spacing mechanism for rotating the platen by a single operation through a major portion of one revolution comprising, in combination, a peripherally toothed ratchet wheel coaxial with the platen and fixedly connected therewith adjacent one end of the platen, a pinion adjacent to and coaxial with said ratchet wheel and conversely rotative relatively thereto, an arm fixedly connected at one end thereof with said pinion and extending outwardly from the axis of the pinion, a pawl pivoted on said arm adjacent the opposite end of the arm on an axis parallel to that of said arm and ratchet wheel and adapted for movement into and out of driving engagement with the teeth of said wheel, a spring connected with said arm and pawl to constantly urge said pawl about its pivot in a direction to effect driving engagement of the pawl with said ratchet wheel, an operating handle pivoted for rocking thereof about an axis parallel to that of the pinion and provided adjacent to and concentric with its pivotal axis with a gear sector in mesh with said pinion, a return spring connected with said handle to urge the latter to a normal idle position, an abutment engageable by said arm to determine the normal idle position of the handle, an interponent member pivoted on said arm to swing about an axis parallel to those of the arm and pawl and engageable at opposite edges of said member with said abutment and pawl to hold the pawl out of driving engagement with the ratchet wheel while the handle is in idle position, means on said arm for limiting swinging of said member away from said pawl during strokes of the handle, and means engageable by the pawl to arrest ratchet wheel driving strokes of the pawl and simultaneously jam said pawl against said wheel.
2. In a typewriting machine of the kind having a platen carriage and a roller platen journaled in the carriage, means for facilitating the typing of a longitudinal series of connected form blanks each of a length not exceeding the circumferential dimension of the platen comprising, in combination, two ratchet wheels coaxial with and located adjacent opposite ends of the platen and connected therewith for rotation of said wheels and platen in unison and at the same angular velocity, the number of teeth of one of said ratchet wheels being an aliquot part of the number of teeth of the other wheel, a normally disengaged driving pawl for the wheel having the larger number of teeth, a line spacing handle connected with said pawl for actuating the latter to rotate its associated ratchet wheel to line space the platen by ordinary short line space steps, a pinion adjacent the other ratchet wheel coaxial with and conversely rotative relatively to said wheel, an arm fixed to said

pinion and extending outwardly from the axis of the latter, a driving pawl for said other ratchet wheel pivoted on said arm on an axis parallel to that of said wheel and arm and adapted for movement into and out of driving engagement with said wheel, a spring connected with said last-mentioned pawl and arm to constantly rock the pawl toward wheel driving position, a second operating handle pivoted on the carriage adjacent said pinion for rocking about an axis parallel to that of the pinion and provided adjacent to and concentric with its pivotal axis with a gear sector in mesh with the pinion, a return spring connected with said second handle to urge the latter to a normal idle position, an abutment on the carriage engageable by said arm to determine the idle position of said second handle, an interponent pivoted on said arm to swing about an axis parallel to those of the arm and its connected pawl and engageable at opposite edges of the interponent with said abutment and pawl to hold the pawl out of driving engagement with its associated ratchet wheel while the second handle is in idle position, means for limiting swinging of said interponent about its pivotal axis during strokes of said second handle, and a second abutment on the carriage engageable by the arm-carried pawl to arrest working strokes imparted to the latter by the second handle, the arrangement of the abutments being such that the maximum rotation impartible to the platen by the arm-carried pawl does not exceed 360 degrees and equals a plurality of ordinary line space extents of rotation impartible to the platen by an operation of the first-mentioned handle.

3. In a typewriting machine having a platen carriage, a roller platen journaled in the carriage, and a handle operated pawl and ratchet line spacing mechanism of the normally disengaged pawl type located adjacent one end of the platen for rotating the platen by short steps for ordinary line spacing, the combination of a coarse toothed ratchet wheel coaxial with and held to the platen of the machine adjacent the opposite end of the platen from said ordinary line spacing mechanism, a second and independent handle operated pawl mechanism for driving said coarse toothed ratchet wheel located adjacent said last-mentioned end of said platen and normally disengaged from said ratchet, the number of teeth of said coarse toothed ratchet being an aliquot part of the number of teeth of the ratchet of said ordinary line spacing mechanism, means for confining the working strokes of said last-mentioned pawl mechanism to an invariable

extent such that it actuates the coarse toothed ratchet to rotate the platen through not more than one revolution to an extent equal either to a predetermined number of ordinary line spaces or equal to the difference between such predetermined number of ordinary line spaces and the number of line spaces the platen may have been advancedly rotated since the last preceding operation of said pawl mechanism, means for 10 rotating the platen at will in both directions, and detent means coactive with the teeth of the ratchet of the ordinary line spacing mechanism to yieldingly hold the platen against rotation.

4. In a typewriting machine having a platen 15 carriage, a roller platen journaled in the carriage, and handle operated line spacing mechanism for rotating the platen by short steps for ordinary line spacing, the combination of a coarse toothed ratchet wheel coaxial with the 20 platen and fixedly connected therewith adjacent one end of the platen, a pinion coaxial with and adjacent the ratchet wheel and conversely rotative relatively thereto, an arm rotative with said pinion and extending radially of the ratchet, a 25 driving pawl for said ratchet wheel pivoted on said arm to swing about an axis parallel to that of the ratchet wheel, a spring connected with said arm and pawl to urge the pawl about its pivot into driving engagement with the ratchet 30 wheel, an operating handle pivoted on the carriage for rocking thereof about an axis parallel to that of the pinion and provided with a gear sector concentric with the pivotal axis of the arm and meshing with the pinion, a return 35 spring for said handle, an abutment on the carriage engageable by said arm to arrest return movement of the handle and pawl, an interponent pivoted on the arm to swing about an axis parallel to those of the arm and pawl and 40 interposed between said abutment and pawl to hold the pawl out of engagement with the ratchet wheel in the returned position of the handle, means for limiting swinging of said interponent away from the pawl on working and return 45 strokes of the handle, and means on the carriage for arresting working strokes of the pawl at a predetermined point rendering the pawl ineffective to rotate the platen more than 360 degrees but rendering said pawl effective upon the second 50 one of two immediately successive operations of said handle, without an intermediate line spacing of the platen, to rotate the platen an extent equal to a plurality of ordinary line spaces.

55 LAURENCE B. HILL,
EDSON G. MOSHIER.
